SPOOL OR BOBBIN

Harry D. Clinton, Johnson City, N. Y.

Application September 8, 1939, Serial No. 294,023

7 Claims. (Cl. 242—123)

This invention relates to spools and bobbins, or to improvements therein, having reference more particularly to textile spools and bobbins of the different kinds or types used for various operation purposes in textile mills.

One of the objects of the invention is to provide a specially strong but light-weight spool or bobbin capable of withstanding the heavy stresses and other forces to which these articles are subjected in modern high-pressure production practices; that is, a spool or bobbin much stronger and lighter than the ordinary like article, which will successfully and durably sustain the effects of high rotational speed winding and twisting, steaming, and knocking about, without warping, swelling, splitting or loosening apart.

Another of the objects is to provide such a spool or bobbin having a high degree of accuracy in the form, balance and concentricity of its parts, closely approaching that of static or perfect balance permitting rotation at extremely high speeds without any throw from true center resulting in warble or vibration.

Combined with said objects, the general aim and purpose is to provide an improved practicable spool or bobbin construction adaptable to the different forms or types and sizes in which such articles are used, and affording a machinability and assembly of the parts with ease and precision.

An illustrative spool embodying the invention in one practicable form is shown for example in the accompanying drawings, by reference to which in further description of the same herein-after the invention will be readily understood.

In said drawings:

Fig. 1 is a perspective view of the barrel blank; Fig. 2 is a similar view of the finished barrel with head and attachment means at one end in separated applicative relation thereto;

Fig. 3 is a longitudinal section view of the complete spool, taken diametrically thereof;

Fig. 4 is a like section of the same spool having an inner fitted core or bearing member, taken somewhat off the diametrical on the line of a chord;

Fig. 5 is a similar section of the same spool having a separately attached inner core or bearing member.

Fig. 6 is a longitudinal section of a modification of the spool formed with separate core parts at opposite ends;

Fig. 7 is a plan or end elevation view of the top of the spool of Fig. 6; and

Fig. 8 is a corresponding plan or end elevation of the bottom of said spool.

In the illustrative spool embodiment, the barrel or body part comprises a length of a specially formed tubular bar 10 of a generally cylindrical contouration. Said tubular bar, preferably composed of metal, consists in this instance of magnesium alloy which has been found to be particularly suitable because of its exceptional strength and lightness, and also because of its excellent machinability. It constitutes structurally a very thin wall or mere shell member having a plurality of integral longitudinal rigidifying and reinforcing ribs 10^a on its inner side spaced therearound equidistantly, said ribs being substantially semi-circular in cross section. This special formation in the case of magnesium alloy or other metal composition is advantageously produced by extrusion of the metal in a molten state through suitable forming dies. It might of course be produced by casting, or in the case of Bakelite or some other toolable material by lathing or some other cutting operation. It will be understood that the generally cylindrical bar member may be polygonal instead of absolutely circular in cross section, and that the aforesaid integral ribs may have some other than the stated shaping, such as triangular or square.

The section of tubular bar 10 comprising the barrel is machined to the proper length and true-ness—referring to axial balance and end plumb-ing—after which it is drilled endwise with screw-holes 11 in the integral ribs thereof at either end (see Fig. 2), preferably though not necessarily in each of said ribs, depending upon the number, the said holes being concentrically centered around the longitudinal axis and parallel therewith. These holes are made somewhat smaller than the thread diameter of the screws they are to receive and are themselves unthreaded or smooth sided.

To the hole-drilled end of said barrel bar a head 12 of disc-plate form in this instance is applied. This head preferably consists of a strong metal such as stainless steel or the like, and will desirably be surface or rim hardened to resist nicking and other common defections. However, hard vulcanized fibre, or any other appropriate material, may instead be used. Holes 13 formed through its thickness in correspondence with the holes drilled in said barrel end render it applicable for attachment thereto, said holes being desirably counter-sunk in its outer face to provide a counterseating for the attaching screws. It is attached by screws 14

30

passed through these holes into the holes of the barrel, the said screws being preferably hard metal screws of the special kind known as "self-threading" or "tapping" screws which cut their own threads into the metal when driven into place, and which may advantageously be permitted to thread into the holes of the head as well as those of the barrel. A central aperture 15 in the head provides for rotational support upon a shaft or gudgeons.

A complete spool with a head at each end of the barrel is shown in Fig. 3. Of course, only one head applied to one end would be used in the case of a "cop" or the like single-head bobbin, in which event the opposite end would be capped with a mere face-over head of the same diameter as the barrel. It will be understood that the actual form of the head applied to either or both ends is a matter of choice according to the kind or type of spool or bobbin to be produced, the fundamental construction being applicable to the various forms of such articles used in the textile industry. The same is true with reference to size, there being no limitation in this respect. This fundamental construction of the invention is, however, especially applicable to any bobbin or spool that is to revolve at high speed, requiring extreme accuracy in its form, and a precise if not absolutely static balance and concentricity. It also applies especially to any bobbin or spool that is to be used for "steaming" or setting the twist on yarn, such as "take-up" bobbins or "winder" spindles, in which cases either solid or hollow pintles may be fixed in the central apertures of the heads as is common to this type of such articles. Still further, this fundamental construction is applicable with particular advantage to wire spools to be used in connection with very fine spun wire.

In certain if not most cases it will be desirable to provide the spool with better gudgeon supportive bearings than the central apertures 15 in their heads alone afford. This may be done in a number of different ways.

Fig. 4 illustrates one practicable means of providing a gudgeon bearing or bushing which is probably also the simplest. In this provision a central core or filler 16 of wood is fitted loosely in the barrel, said core having opposite end portions 16^a bearing close against the surrounding ribs 10^a of the barrel so as to be centered and held frictionally therewithin and being axially bored in register with the central apertures of the heads so as to receive the extension of the gudgeons thereinto. This core or filler is merely inserted before the last of the heads is applied and its ends may extend against or substantially against the inner sides of said heads. While wood is used as the material of the core in this instance, it may of course be made of some other material such as fibre composition.

Fig. 5 illustrates another practicable means of providing such a bearing or bushing. In this case a relatively thin metal tube 17 is extended axially through the spool with its ends 17^a swaged over in counter-sink upon the outer sides of the heads around their central apertures. To accommodate this arrangement of course it is necessary for said central apertures of the heads to be made slightly larger than normal, to the extent of the thickness of the tube, and the tube must of course be of an inner diameter to receive the gudgeons upon which the spool is meant to fit.

The modification of Fig. 6 illustrates what may

be the ordinarily preferred bearing or bushing provision. In this provision a metal sleeve 18 is fitted into the intended top or upper end of the spool through the central aperture of the head at that end. This sleeve has an outer peripheral 5 or lateral flange 18^a seating upon the outer face of said head and formed with holes (not referenced) registering with the screw holes in the head and barrel end. The regular attaching screws 14 are passed through these holes to fasten 10 it tight upon the head as the latter is itself attached to the barrel. Similarly, at the intended bottom or lower end of the spool, a substantially corresponding metal sleeve 19 is applied by its flange 19^a, the latter in this instance however 15 being specially formed in its outer end with a diametrical coss slot 20 so as at the same time to provide a "twister" attachment to the head at that end.

The described spool or bobbin will obviously be 20 exceptionally strong and sturdy, especially when made entirely of metal as will generally be preferred. In addition it has the decided advantage that it is machinable in all its parts to a high degree of accuracy and precision, whereby 25 it is not only made true and perfectly balanced but its heads are exactly angulated against the barrel with tight and absolutely closed union between the two. Another very important advantage is that it is substantially indestructible and 30 impervious to moisture and heat so that it can be used in regular "steaming" operations without warping, swelling, cracking or loosening apart. Any possible electrolytic action between the magnesium barrel and a hard steel head may 35 be prevented by applying Bakelite varnish between the two metals and the magnesium barrel itself may advantageously be coated with a protective varnish film. Tests have shown that it is virtually impossible to remove the heads from 40 the barrel and that the attaching screws themselves must be broken under a tremendous force before this can actually be done, while the barrel will deform or crush only from intense striking force or pressures applied thereto.

It will be understood from the foregoing specification that certain variations and substitutions can be made in the form and composition of the parts of the spool wholly within the allowable scope and essentials of the invention. It is 50 therefore not intended to limit the invention by the following claims to the specific forms and compositions, or to the specific construction illustrated and described herein, beyond what said claims by their terms themselves impose.

Having thus described my invention, what I claim as new and desire to secure by Letters Patent of the United States is as follows:

1. A spool or bobbin, comprising a flangeless cylindric barrel consisting of a length of a tubular thin-wall body of magnesium alloy having a plurality of unconnected integrally formed cross-sectionally solid longitudinal ribs on its inner side spaced equidistantly therearound and extending the full length thereof, a separate 65 flanging head of a hard material composition on each end of the barrel, and metal screw elements passed through said heads into and in threaded engagement with said ribs of the barrel endwise of the latter so as to clampably attach the heads to the barrel at said ends.

2. In a spool or bobbin construction embodying a wholly unitary flangeless barrel of cylindric form and a separate flanging disc form head attached thereto, the improvement which con- 75

sists in the provision of the barrel by a tubular thin-wall body member comprising a strong solid material formed with a plurality of unconnected integrally formed solid longitudinal ribs on its inner side spaced circumferentially therearound and extending the full length thereof, said ribs serving to rigidify and strengtheningly reinforce the said body member and providing definite circumferential areas of mass of the material thereof of sufficient thickness to serve for the reception of the head attaching means, said means constituting screw-like elements extended through the head into and in threaded engagement with the said ribs so as to clampably secure the head at either end of the barrel.

3. In a spool or bobbin construction embodying a wholly complete flangeless barrel of cylindrical form and a separate flanging disc form head attached thereto, the improvement which consists in the provision of the barrel by a tubular thin-wall body member comprising a solid magnesium alloy material formed with a plurality of unconnected integrally formed solid longitudinal ribs on its inner side spaced circumferentially therearound and extending the full length thereof, said ribs serving to rigidify and strengtheningly reinforce the said body member and providing definite circumferentially disposed areas of mass of the material at the ends thereof of sufficient thickness to serve for the reception of the head attaching means thereto, the said means constituting screw-like elements extended through the head into and in threaded engagement with the said ribs so as to clampably draw and secure the head at either end of the barrel.

4. In a spool or bobbin construction embodying a wholly unitary flangeless barrel of cylindrical form and separate flanging disc form heads attached thereto at opposite ends, the improvement which consists in the provision of the barrel by a tubular thin-wall body member comprising a strong solid material formed with a plurality of unconnected integrally formed solid longitudinal ribs on its inner side spaced circumferentially therearound at equal distances apart and extending the full length thereof, said ribs serving to rigidify and strengthenly reinforce

the said body member and providing predetermined definite areas of mass of the material thereof of sufficient thickness to serve for the reception of the means attaching the heads thereto, the said means constituting screw-like elements extended through the heads into and in threaded engagement with the said ribs so as to clampably secure the heads at opposite ends of the barrel.

5. In a spool or bobbin construction embodying a wholly unitary flangeless barrel of cylindrical form and separate flanging disc form heads attached thereto at opposite ends, the improvement which consists in the provision of the barrel by a tubular thin-wall body member comprising a solid magnesium alloy material formed with a plurality of unconnected integrally formed solid longitudinal ribs on its inner side spaced circumferentially therearound at equal distances apart and extending the full length thereof, said ribs serving to rigidify and strengtheningly reinforce the said body member and providing definite circumferentially spaced areas of mass of the material thereof of sufficient thickness to serve for the reception of the means attaching the heads to the ends of the same, the said means constituting screw-like elements extended through the heads into and in self-threading engagement with the said ribs so as to clampably draw and secure the heads broadside against opposite ends of the barrel.

6. A spool or bobbin according to claim 1, including a core bushing therein extending axially through the barrel with a centering peripheral fit close against the longitudinal edges of the ribs surrounding the same and providing gudgeon bearings in the opposite ends of said spool.

7. A spool or bobbin according to claim 1, including separate bushing sleeves providing gudgeon bearings in opposite ends of the spool or bobbin fastened in place along with the head at each end by the attaching screw elements passed therethrough into the ribs of the barrel, one of said bushings being formed to provide a "twister" attachment for the spool at one end.

HARRY D. CLINTON.
